COMBINED CANDLE AND PRAYER CARD HOLDER

Alex P. Le Vay, Dayton, Ohio

Application May 13, 1957, Serial No. 46,119

Term of patent 14 years

(Cl. D48—2)

FIG-1

Figure 1 is a perspective view of a combined candle and prayer card holder, showing my new design;

The broken line showing of a prayer card in Figure 1 is for purpose of illustration only.

I claim:

The ornamental design for a combined candle and prayer card holder, as shown and described.
